UNITED STATES PATENT OFFICE.

DAVID BOYLE, OF PATERSON, NEW JERSEY.

CARBONATOR.

SPECIFICATION forming part of Letters Patent No. 628,137, dated July 4, 1899.

Application filed December 16, 1898. Serial No. 699,419. (No model.)

To all whom it may concern:

Be it known that I, DAVID BOYLE, a citizen of the United States, residing in Paterson, in the county of Passaic and State of New Jersey, have invented certain new and useful Improvements in Carbonators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an apparatus for carbonating water and other liquids.

The principal object of the invention is to provide means whereby the liquid to be carbonated is not only broken up into myriads of small particles, but while in this state is also considerably and thoroughly agitated, so that the mechanical combination between the liquid and the gas is most completely effected.

The invention consists in the improved carbonating apparatus and in the combination and arrangement of its various parts, substantially as will be hereinafter pointed out and finally embodied in the clauses of the claim.

Referring to the accompanying drawings, Figure 1 is a view showing my improved carbonating apparatus, partly in section. Fig. 2 is a top plan view of said apparatus. Fig. 3 is a vertical sectional view of a portion of the upper end of the apparatus, and Fig. 4 is a sectional view of the upper portion of an apparatus constituting a slight modification of my invention.

In said drawings, *a* designates a vertical cylinder having an integral flange *a'* at its lower edge, whereby through the medium of bolts or screws *b* it is secured to a base *b'*. *c* indicates a cap which is screwed into and surmounts said cylinder.

c' designates a vertical revoluble shaft which is stepped at its lower end in the base *b'* and which at its upper end penetrates the cap *c*, being surrounded by a stuffing-box *d* of ordinary construction upon said cap. This shaft is adapted to be rotated in any suitable manner—as, for instance, by means of a belt passing over a pulley *d'*, keyed upon, preferably, the upper end of said shaft. The

shaft *c'* carries a series of paddles *e*, which may be formed into integral sets of substantially propeller-like shape, each propeller or set of blades being preferably adjustably mounted on said shaft by means of a set-screw *e'*. Alternating with said propellers and likewise preferably adjustably mounted on said shaft are shallow perforated cups *f*, each cup being most desirably disposed in proximity to the propeller above it. It should be remarked that both the propellers and the cups are nearly of the same diameter as the cylinder in the preferred form of my apparatus.

f' designates a pipe communicating with the source of water-supply at one end, as hereinafter described, and projecting at its other end into the cylinder, extending through the cap thereof, in which it is screwed, and provided at its free end with a rose or spray *g*.

g' constitutes the conducting-pipe for the carbonic-acid gas. This pipe communicates with the cylinder *h*, containing the supply, through a short tube *h'*, in which is arranged a pressure-gage *i*, and said pipe *g'* communicates with the cylinder *a* at points preferably between each propeller and its corresponding cup through other short tubes *i'*.

j designates a valve whereby the supply of gas to the pipe *g'* and ultimately to the cylinder is controlled, said valve being arranged in the pipe *h'*.

The lower end of the water-supply pipe is connected to a coil *j'*, which surrounds the cylinder at its base, through the medium of a valve *k*, situated within the cylinder (into which the coincident ends of said pipe and coil project for this purpose) and controlled by a ball-float *k'*, also situated in said cylinder. The coil *j'* is directly connected with the source or supply of water. Said coil, furthermore, is inclosed within a jacket *l*, forming, with the cylinder and its base, a tank, within which and between said cylinder and the coil may be placed ice for refrigerating the water as it comes from the supply.

l' designates a gage communicating with the cylinder through the pipes *m m'*, controlled by the valves *n n'*, respectively, and adapted to indicate the height of the liquid that has been carbonated and collected in the bottom of the cylinder. *o* is a thermome-

ter projecting out of said gage, at the upper end thereof, and o' is a small cock communicating with the lower end of said gage.

p indicates one of the discharge-pipes of the apparatus. It is provided at its free end with one or more nozzles p' , controlled by valves q and to which the tubes connecting said apparatus with the bottles or other receptacles for the carbonated liquid may be applied. Several of these pipes p may be provided. Besides the one already described I have indicated at q' where another one may be connected with the apparatus; but it is manifest that these pipes may have connection with the cylinder at any point below the normal surface of the charged liquid, as desired. It is only necessary here to remark that the liquid may be more or less completely charged at one level than at another for various reasons, and hence it may be desirable to provide a number of the pipes p , so that the operator may select the one whereby the liquid of the desired quality may be discharged.

In order that the air which collects in the top of the cylinder may be automatically allowed to escape, I have provided a valve r , controlling the pipe r' , that extends through the cap c , said valve being carried by an angular lever s , fulcrumed upon the top of said pipe and normally held downwardly—that is to say, with the valve closed—by means of a spring s' , connected to the cap. The lever s is operated and the valve opened by means of pins t , carried upon one side of a worm-wheel t' , whose teeth engage a worm u on the shaft c' , said wheel being journaled upon a standard u' and projecting upwardly from and secured to the cap c . It should be remarked that the pins t are preferably removable from the wheel in which they are mounted. This provision is made in order that the number of pins which are acting upon the lever s may be varied according to the number of bottlers operating the apparatus.

If necessary, a safety-valve v , controlled by a weighted lever v' , may be arranged upon the cap c , so that in case the pressure of the gas becomes abnormal it may escape whether or not the valve r is opened frequently enough to accomplish this end.

In the modification shown in Fig. 4 the vertical chamber w , which corresponds to the cylinder a , is preferably rectangular in cross-section. In said modification the paddle-blades or propellers w' are revoluble in vertical planes, being mounted upon horizontal shafts x , journaled in bearing-blocks x' , disposed in opposite walls of the chamber w , said shafts being rotated by means of a single vertical shaft y , revolvably arranged outside of the chamber and carrying pinions y' , engaging pinions z on the horizontal shafts. It should be remarked that the paddles of each set are in alternate arrangement with those above and below them. Instead of the cups f perforated troughs z' are mounted below each series of paddles w' . The escape of

the air is, in the case of this modification, permitted by means of a spring-actuated valve a' , arranged upon and controlling a pipe b' , 70 screwed into the cap c' of the chamber, said valve being actuated by pins d' , carried upon a disk e' , that is keyed upon the shaft y . For the purpose hereinbefore set forth the said pins may be removable. The mechanism on the lower end of this apparatus is substantially like that hereinbefore described and shown in Fig. 1 with reference to the preferred form of the apparatus. The gas is supplied in substantially the same manner as hereinbefore described with reference to said preferred form of the apparatus; but the water is discharged from the supply-pipe f' through the medium of a perforated pipe f'' , that extends across the chamber at its upper end. 85

It should be remarked that if desirable the pipe g' may be provided with an extension g'' , which will convey the gas into the cylinder at a point below the level of the liquid that has collected after having been carbonated. Thus provision is made for a further carbonating of the liquid.

In operation, water being admitted from its supply and gas being admitted from the cylinder h , the former will flow through the coil and the pipe f' , being finally discharged from the rose g , whereby it is sprayed downwardly, and simultaneously the gas passes from its cylinder through the pipe g' and the smaller pipes i' and g'' into the main cylinder, wherein it immediately begins to rise. Meanwhile the shaft c'' and the propellers and perforated disks which it carries are being rotated at a high rate of speed, the consequence being that the water which is being sprayed from the rose g is continually being further broken up into smaller particles by the blades or paddles and caused to thoroughly commingle with the rising gas, which is likewise and through the same medium being broken up into myriads of particles. Owing to the rapid rotation of the propellers, there is a more or less tendency to drive back several times the water and the gas as, in its divided state, it meets said revolving propellers, so that the effect of the commingling the water and the gas is not only produced by virtue of the fact that each is broken up into a great number of minute particles but also to the fact that their progress through the apparatus is greatly retarded.

The principal function of the perforated disks is to deliver the liquid to the subjacent rapidly-rotating blades or paddles in a finely divided or comminuted state, so that the bodies of liquid which engage said blades and which are by them violently agitated to effect the desired commingling of liquid and gas may be as small and as numerous as possible and directed against each entire blade. Furthermore, it is the function of the paddles to not only continue but to materially augment the breaking up of the liquid into small particles and the effectuation of its commingling.

with the rising gas, and hence said blades or paddles are of comparatively small size, have appreciable inclination, and are considerably separated.

5 I am aware that it is old to employ perforated partitions or their equivalents for breaking up the liquid into small quantities or bodies as it passes through the apparatus and is subjected to the rising gas. I am also aware
10 that it is old to employ blades or paddles to agitate the descending liquid; but I am not aware that it is old to employ these two elements—namely, the blades or paddles and the perforated disks or other partitions—in
15 combination and of the character and in the disposition described for the purposes of securing the peculiar results above particularly referred to.

As the carbonated water collects at the bottom, it gradually rises if not immediately drawn off until the ball-float rises and shuts off the supply of water. Meanwhile the air that is being formed is being intermittently permitted to escape by means of the automatic valve *r*. As soon as the liquid which
25 has been carbonated is sufficiently drawn off by the bottler or bottlers the float will again descend and permit more water to enter the apparatus. If no water appears in the gage
30 *l*, it will be obvious to the attendant that water is not being supplied.

It is to be noted that the disposition of the refrigerating apparatus relatively to the liquid-supply by virtue of the arrangement of the
35 coil *j* in the refrigerating-chamber itself is such that not only is the liquid already carbonated and collected in the bottom of the cylinder kept cool, but the newly-carbonated liquid falling into it has practically the same
40 temperature.

I have hereinbefore particularly referred to water as the liquid to be carbonated; but it is obvious that the various beverages or liquids which are usually subjected to the carbonating treatment may be treated by means
45 of my apparatus.

Having thus fully described my invention, what I claim, and desire to secure by Letters Patent, is—

50 1. The combination with a vertically-arranged elongated chamber, means for admitting the liquid to be carbonated at the upper end thereof and the carbonating-gas at a point or points in said chamber beneath the point for admitting the liquid, radially arranged and inclined blades or paddles disposed in series situated the one above the other and beneath the point of liquid admission, the blades or paddles of each series being appreciably out of vertical coincidence with each other, perforated partitions arranged alternately with said sets of blades, and means for rotating said sets of blades or paddles, substantially as described.

65 2. The combination of a vertically-arranged elongated chamber, a liquid-supply pipe communicating with said chamber at its upper

end, a pipe for the carbonating-gas having a plurality of communications with said chamber situated beneath the discharge-point of the liquid-supply pipe, radially arranged and inclined blades or paddles disposed in series situated the one above the other and each above a point of discharge from the gas-supply pipe, the blades or paddles of each series being appreciably out of vertical coincidence with each other, means for rotating said sets of blades or paddles and perforated partitions alternately arranged in said chamber with said paddles and disposed beneath said points of discharge from the gas-supply pipe, substantially as described.

3. The combination of a vertically-arranged elongated chamber, a liquid-supply pipe communicating with said chamber at its upper end, a pipe for the carbonating-gas having a plurality of communications with said chamber situated beneath the point of discharge of the liquid, radially arranged and inclined blades or paddles disposed in series situated the one above the other and each above a point of discharge from the gas-supply pipe, the blades or paddles of each series being appreciably out of vertical coincidence with each other, perforated partitions alternately arranged in said chamber with said blades or paddles and disposed beneath said points of discharge from the gas-supply pipe, and a revoluble shaft having suitable bearings and being operatively connected to, and adapted to rotate, said sets of blades or paddles, substantially as described.

4. The combination of a vertically-arranged elongated chamber, a liquid-supply pipe communicating with said chamber at its upper end, a pipe for the carbonating-gas having a plurality of communications with said chamber situated beneath the point of discharge of the liquid, radially arranged and inclined blades or paddles disposed in series situated the one above the other and each above a point of discharge from the gas-supply pipe, the blades or paddles of each series being appreciably out of vertical coincidence with each other, perforated partitions alternately arranged in said chamber with said blades or paddles and disposed beneath said points of discharge from the gas-supply pipe, a revoluble shaft having suitable bearings and being operatively connected to, and adapted to rotate, said sets of blades or paddles, a suitable discharge at the lower end of the chamber and a ball-float arranged in said chamber and controlling the liquid-supply, substantially as described.

5. The combination of a vertically-arranged elongated chamber, a liquid-supply pipe communicating with said chamber at its upper end, a pipe for the carbonating-gas having a plurality of communications with said chamber situated beneath the point of discharge of the liquid, radially arranged and inclined blades or paddles disposed in series situated the one above the other and each above a

- point of discharge from the gas-supply pipe, the blades or paddles of each series being appreciably out of vertical coincidence with each other, perforated partitions alternately arranged in said chamber with said blades or paddles and disposed beneath said points of discharge from the gas-supply pipe, a revolute shaft having suitable bearings and being operatively connected to, and adapted to rotate, said sets of blades or paddles, a suitable discharge at the lower end of said chamber, a coil surrounding said chamber and constituting a portion of the liquid-supply pipe, a jacket surrounding said chamber and the coil and constituting a receptacle for a refrigerating medium, and a ball-float arranged in said chamber and controlling the liquid-supply pipe, substantially as described.
6. The combination of a vertically-arranged elongated chamber, a liquid-supply pipe communicating with said chamber at its upper end, a pipe for the carbonating-gas having one or more communications with said chamber situated beneath the discharge-point and the liquid-supply pipe, sets of inclined blades or paddles each disposed above a point of discharge from the gas-supply pipe, perforated partitions arranged in said chamber beneath said points of discharge from the gas-supply pipe, a revolute shaft having suitable bearings and being operatively connected to, and adapted to rotate, said sets of blades or paddles, a suitable discharge at the lower end of said chamber, a coil surrounding said chamber and constituting a portion of the liquid-supply pipe, a jacket surrounding said chamber and the coil, a ball-float arranged in said chamber and controlling the liquid-supply pipe, a valve in the top of said chamber, actuating means therefor operatively connected to said shaft, a liquid-gage communicating with said chamber, and a spray or rose connected to and constituting the terminus of the liquid-supply pipe, substantially as described.
7. The combination of a vertically-arranged elongated chamber, a liquid-supply pipe communicating with said chamber at its upper end, a pipe for the carbonating-gas having one or more communications with said chamber situated beneath the discharge-point and the liquid-supply pipe, sets of inclined blades or paddles each disposed above a point of discharge from the gas-supply pipe, perforated partitions arranged in said chamber beneath said points of discharge from the gas-supply pipe, a revolute shaft having suitable bearings and being operatively connected to, and adapted to rotate, said sets of blades or paddles, a suitable discharge at the lower end of said chamber, a coil surrounding said chamber and constituting a portion of the liquid-supply pipe, a jacket surrounding said chamber and the coil, a ball-float arranged in said chamber and controlling the liquid-supply pipe, a valve in the top of said chamber, actuating means therefor operatively connected to said shaft, a liquid-gage communicating with said chamber, and a spray or rose connected to and constituting the terminus of the liquid-supply pipe, substantially as described.
- In testimony that I claim the foregoing I have hereunto set my hand this 10th day of December, 1898.
- DAVID BOYLE.
